SHINGLING BRACKET

Russell S. Smith, Alford, Mass.
(R.F.D. 3, Great Barrington, Mass. 01230)

Filed Oct. 6, 1971, Ser. No. 187,212

Term of patent 14 years

Int. Cl. D8—08

U.S. Cl. D54—1 A

FIG. 1

FIG. 2

FIG. 4

FIG. 3

FIG. 1 is a perspective view of the shingling bracket embodying my new design.

FIG. 2 is a plan view of the same embodiment.

FIG. 3 is a side view of the same embodiment.

FIG. 4 is an end view of the same embodiment as viewed in the direction of the arrows 4-4 of FIG. 3.

I claim:

The ornamental design for a shingling bracket, as shown.
